UNITED STATES PATENT OFFICE

2,548,649

MECHANICAL PENCIL WITH LEAD SHARPENING DEVICE

William E. Brady, Parma, Ohio

Application December 7, 1949, Serial No. 131,640

1 Claim. (Cl. 120—15)

1 This invention relates to mechanical pencils, and aims to provide a lead sharpening device which is permanently attached thereto, and which may be readily and easily brought into operation by the movement of the fingers gripping the pencil in writing, the lead of the pencil being then rotated under the sharpening device thereby forming a writing point on the lead of the pencil.

An important object of the invention is to improve generally the construction as shown and described in my Patent Number 2,432,376, granted under date of December 9, 1947.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawing

Figure 1 is an elevational view of a mechanical pencil equipped with a sharpening device constructed in accordance with the invention.

Fig. 2 is a plan view illustrating the improved structure.

Fig. 3 is a longitudinal sectional view through the pointed end of the barrel of the pencil, illustrating the lead sharpening mechanism.

Fig. 4 is a perspective view of the sharpening blade.

Fig. 5 is a fragmental longitudinal sectional view through the pointed end of the pencil, illustrating the sharpening device as in its sharpening position.

Fig. 6 is a sectional view illustrating the sharpening mechanism as operated to form a chisel-like point on the lead of the pencil.

Fig. 7 is a sectional view taken on line 7—7 of Fig. 3.

Fig. 8 is a fragmental sectional view illustrating the tapered or writing end of the pencil as threaded into one end of the pencil barrel.

Referring to the drawing in detail, the body portion or barrel of the mechanical pencil, is indicated generally by the reference character 5 and the reference character 6 indicates the pointed end of the barrel which is provided with a removable tapered end section 7, the pointed end 6 of the barrel being provided with a recess in its outer end, to accommodate the extension 8 of the tapered end section 7.

The pencil includes an extension 9 that fits

2 into the recess 10 formed in the inner end of the pointed end 6 of the barrel, the connection between the extension 9 and the pointed end 6 of the barrel being such that the main portion of the pencil may swivel with respect to the tapered end 6 to rotate the lead which in the present showing is indicated by the reference character 11.

The outer surface of the pointed end 6 of the barrel, is formed with a recess which is disposed longitudinally of the pointed end of the barrel, the recess being indicated by the reference character 11'. The recess 11' continues throughout the length of the tapered end section 7, so that the blade 13 may slide throughout the length of the pointed end 6 of the barrel, and continue throughout the length of the tapered end 7, where the blade may be extended beyond the end of the tapered end 7 to contact the lead 11.

20 Ribs 14 are formed along the longitudinal side edges of the blade 13, and slide in grooves formed in the walls of the recess 10.

At one end of the blade 13, is an eye through which one end of the spring 15 extends, the opposite end of the spring being secured within the inner end of the recess 10 so that as the blade is moved forwardly, the spring 15 will be placed under tension to return the blade to its normal inactive position, after the sharpening of the lead of the pencil.

30 Formed within the blade 13, is an elongated opening 16 which has the cutting blade 17 formed along one wall of the elongated opening and disposed longitudinally of the blade, to operate at right angles to the side of the lead being sharpened.

The forward end of the blade is beveled as at 18 providing a chisel cutting edge which when moved over one side of the lead of the pencil, will sharpen the lead forming a chisel-like edge on the lead, as shown by Fig. 6 of the drawing.

40 The upper surface of the blade 13 is knurled as at 19 to permit the operator to press his finger against the blade to move the blade longitudinally of the pointed end of the barrel to move the blade to its active or lead sharpening position, after which the lead is returned by the spring 15, as previously described.

As shown by Fig. 8 of the drawing, the tapered end section 20 is provided with a threaded extension 21 that is fitted in the threaded recess 22 formed in one end of the pointed end 23 of this form of the barrel.

50 In use, when the lead of the pencil becomes broken, the mechanical pencil is operated in the

usual way to project a length of the lead beyond the pointed end of the pencil barrel. The blade now is moved forwardly until the cutting blade 17 thereof is directly over the extended end of the lead of the pencil, whereupon the pencil barrel is rotated rotating the lead under the knife to sharpen the same into a fine writing point.

When the blade is released, the spring will return the blade to its position within the recess 10, where it will be out of the way of the fingers holding the pencil, during writing.

Having thus described the invention, what is claimed is:

The combination with a lead pencil including a main portion in which the lead of the pencil is secured, and a tapered end member having swivel connection therewith, through which the pencil lead extends, said tapered end having a longitudinally disposed recess, a lead sharpening blade movable longitudinally of the re-

cess, said blade having an elongated opening formed therein, one wall of the opening forming a blade for sharpening lead with which the blade contacts, and the outer end of said blade being beveled providing an auxiliary cutting edge whereby the lead of the pencil is beveled into chisel-like form.
